DESIGN FOR A CLOSURE CAP OR SIMILAR ARTICLE

Joseph R. Fleisch, Clifton, N. J., assignor to Anchor Cap & Closure Corporation, Long
Island City, N. Y., a corporation of New York

Application February 20, 1934, Serial No. 50,787

Term of patent 14 years

To all whom it may concern:

Be it known that I, JOSEPH R. FLEISCH, a citizen of the United States, residing in Clifton, county of Passaic, State of New Jersey, have invented a new, original, and ornamental Design for a Closure Cap or Similar Article, of which the following is a specification, reference being had to the accompanying drawing, forming a part thereof.

The figure is a perspective view of a closure cap or similar article, showing my new design.

I claim:

The ornamental design for a closure cap or similar article, substantially as shown.

In witness whereof, I have hereunto affixed my hand and seal, this 7th day of February, 1934.

JOSEPH R. FLEISCH.
